United States Patent Office

Des. 208,126

Patented July 18, 1967

208,126

PLASTIC SHEET MATERIAL OR THE LIKE

Gilbert D. Endrizzi, Wisconsin Rapids, Wis., assignor to Consoweld Corporation, Wisconsin Rapids, Wis., a corporation of Wisconsin

Filed Mar. 4, 1966, Ser. No. 1,292

Term of patent 14 years

(Cl. D87—3)

The drawing is a plan view of a plastic sheet material showing my new design wherein the design unit is repeated in regular succession as indicated by the extensions beyond the unit boundaries.

I claim:

The ornamental design for plastic sheet material or the like, substantially as shown and described.
